UNITED STATES PATENT OFFICE

146,501

DESIGN FOR A VIBRATING JOGGER FOR
PAPER SHEETS OR THE LIKE

Fred A. Hacker, Cranford, N. J., assignor, by
mesne assignments, to American Type Found-
ers, Incorporated, Elizabeth, N. J., a corporation
of New Jersey

Application March 28, 1946, Serial No. 128,037

Term of patent 14 years

(Cl. D64—11)

To all whom it may concern:

Be it known that I, Fred A. Hacker, a citizen of the United States, residing in the town of Cranford, county of Union, and State of New Jersey, have invented a new, original, and ornamental Design for Vibrating Jogger for Paper Sheets or the like, of which the following is a specification, reference being had to the accompanying drawing, forming part thereof, and in which

Figure 1 is a view in perspective of a jogger table showing my novel design; and

Figure 2 is a view in front elevation of the same device.

The characteristic features of my design reside in the configuration of the base portion of the jogger in association with an overhanging top or table portion, as shown.

I claim as my invention:

The ornamental design for a vibrating jogger for paper sheets or the like, as shown and de-
scribed.

FRED A. HACKER.
